UNITED STATES PATENT OFFICE.

CHARLES E. DURYEA, OF SAGINAW, MICHIGAN.

COOLING SYSTEM FOR MOTORS.

1,156,067.

Specification of Letters Patent. Patented Oct. 12, 1915.

Application filed June 11, 1912. Serial No. 702,941.

To all whom it may concern:

Be it known that I, CHARLES E. DURYEA, a citizen of the United States of America, and resident of Saginaw, in the county of Saginaw and State of Michigan, have invented certain new and useful Improvements in Cooling Systems for Motors, of which the following is a specification.

This invention relates to certain new and useful improvements in that class of motors in which the cooling is accomplished by a blast of air from a power-driven fan.

The present invention has for its object among others to provide a simple, certain, and easily assembled arrangement of the various parts so combined as to produce superior results.

I provide a construction which is particularly adapted for automobile purposes, although, of course, not restricted to such use.

Other objects and advantages of the invention will hereinafter appear and the novel features thereof will be particularly pointed out in the appended claims.

The invention is capable of embodiment in a variety of forms, that herein shown being what I at the present time consider preferable.

The invention, in such preferred form, as clearly illustrated in the accompanying drawings, which, with the numerals of reference marked thereon, form a part of this specification, and in which—

Figure 1 is an elevation. Fig. 2 is a plan with portions broken away. Fig. 3 is a detail of a portion of the fly wheel, in section, with two of its vanes or blades.

Like numerals of reference indicate like parts throughout the different views.

In carrying out my invention, in order to secure a blast of air without additional bearings or driving means, I fit to the fly wheel 1 suitably shaped vanes 2, so that when revolving a blast of air is thrown from the center of the wheel out in all directions toward its periphery. I can catch this air by any suitable case, such as the more or less eccentric form of case commonly used in centrifugal blowers, but sufficient for my purpose I have found to be a case 3, which is affixed to the frame of the engine in such a way as to house approximately one-half of the fly wheel 1. While, of course, this case may be so shaped as to carry the air to any one cylinder or to more than one cylinder, I preferably employ this arrangement in con-

nection with a motor having two cylinders 3^a, 3^b, and having the fly wheel 1 placed between them. Further, while I may use vanes 2, 2 on one side only of the fly wheel, I have preferred to use them on both sides, as shown in Fig. 2, for the reason that they seem to fill with air more readily if they are not so deep. Having the fly wheel 1 placed between the cylinders 3^a, 3^b and incased on that semi-circumference nearest the cylinders, I further extend the casing 3 to the cylinder heads by branches 4, 4 terminating in enlarged openings 5, 5, which rest against the cylinder heads 6, 6, secured thereto by the spark plugs 7, 7, or any similar fastening, such as the usual support for the cylinder head, not shown. Joining the opening 5 and surrounding each cylinder is a cylindrical case, 8, through which the air passes along the sides of the cylinder walls, escaping out the rear lower end of said case 8, and carrying with it the heat which it has acquired, by contact with the cylinder walls. To make this heating of the air more certain, I provide the cylinder walls with projections 3^c, either by casting or preferably by machining, so as to leave pyramid-like projections which extend outward in all directions to the inclosing case 8, as seen in Fig. 2. These are usually staggered so that the air cannot pass directly along the walls, but must change its course rapidly, thus exposing all the cool air to the hot metal before the air is permitted to escape. It will be seen that the case 3 with its branches 4, 4 may be removed from the fly wheel and cylinders readily by detaching the spark plugs 7, 7 and the frame screws 9, 9, which removal permits the cylinders with their encircling cases 8, 8 to be as readily removed from the engine as if the construction were of the usual kind. This feature of ready removability is of considerable importance, and this type of engine is particularly adapted for automobile purposes. The engine shown is of the two-cycle type, which has no moving parts outside thereof excepting the fly wheel, and since this is more or less incased, there is no need to house this type of motor, for the cylinders and their cooling projections are amply protected from mud by the encircling cases 8, 8.

In Fig. 3 is seen a section of the fly wheel 1, with the vanes 2, 2 in place thereon. These vanes are commonly attached at the outer edge to a wire 10, and at their inner

edge to a flat ring 11, which hold the vanes in proper position and permit their being affixed to the fly wheel by occasional screws through the flat ring, as shown at 12 in Fig. 5. 1. Other methods of attaching these may be, of course, employed. Likewise the opening 5 of the branch 4 may be made a part of the cylinder case 8, and the line of separation may be at 13, as in Fig. 2, with some 10 suitable covering for the joint instead of separating at the joint 14. The case can be in two parts, as indicated by dotted lines in Fig. 2.

Modifications in detail may be resorted 15 to without departing from the spirit of the invention or sacrificing any of its advantages.

What is claimed as new is:—

1. In a device of the class described, a 20 pair of cylinders, a fly wheel disposed between the same and provided with vanes extended laterally upon the sides of said wheel and constructed when revolving to throw a blast of air from the center of the wheel outward in all directions, and a case inclosing a portion of said wheel for receiving the air from the vanes and having connections for cooling both of said cylinders.

2. In a device of the class described, a fly 30 wheel provided with two sets of removable vanes, one set upon each side thereof extended beyond the side of the wheel, the vanes of each set, being connected together and removable as a whole.

3. In a device of the class described, a 35 pair of cylinders, a casing surrounding one end of each cylinder, a fly wheel disposed between said cylinders and having in sets removable side vanes, conforming to the 40 side of said fly wheel and a case inclosing a portion of said fly wheel and having communication with the casings of the cylinders, the said vanes extending circumferentially around the wheel beyond the side edges 45 thereof.

4. In a device of the class described, a fly 50 wheel with vanes, connected together and removably secured to said wheel, a cylinder, a casing therefor, and a removable casing, the support surrounding the fly wheel and to which said casing is attached and a branch 55 from the fly wheel casing to the casing of the cylinder, said vanes being disposed circumferentially of the wheel upon both sides thereof.

5. In a device of the class described, a 60 cylinder, a casing for one end thereof, a fly wheel by the side of the cylinder and inde-

pendent thereof, a fly wheel case inclosing a portion of said fly wheel, means connecting 60 the interior of the fly wheel case with the said casing, means permitting removal of the casing from the fly wheel without disturbing the cylinder, and draft-producing means carried by said fly wheel. 65

6. In a device of the class described, a cylinder, a casing for one end thereof, a fly wheel having blowing means upon the sides thereof, a casing for a portion of the fly wheel, means leading from said casing to 70 convey air to the cylinder casing for cooling the cylinder, and means permitting removal of the fly wheel casing without disturbing the cylinder and permitting removal of the cylinder from its case without disturbing the 75 fly wheel casing.

7. In a device of the class described, a 80 pair of cylinders, casings for one end thereof, a fly wheel disposed between the cylinders and having vanes, a fly wheel support, a removable case attached to the support surrounding the fly wheel and removable means connected with the fly wheel casing and bearing against the cylinder heads.

8. In a device of the class described, a 85 pair of cylinders, casings for one end thereof, a fly wheel disposed between the cylinders and having removable vanes on opposite sides thereof, those on each side being removable as a unit, a removable case attached to the support surrounding the fly 90 wheel and removable means connected with the fly wheel casing and bearing against the cylinder heads.

9. In a device of the class described, a fly 95 wheel, a plurality of vanes upon either side thereof arranged circumferentially of the wheel and disposed beyond the side edges thereof, means connecting the vanes upon each side of the wheel together at their inner and outer edges; and means detachably 100 engaging the inner connecting means for detachably securing the vanes to the wheel.

10. In a device of the class described, a fly wheel, and a plurality of vanes upon the 105 side thereof arranged circumferentially of the wheel and disposed beyond the side edge thereof, said vanes being connected together as a unit and all removable together.

Signed by me at Saginaw Mich. this 8th 110 day of June 1912.

CHARLES E. DURYEA.
